UNITED STATES PATENT OFFICE

RALPH E. SCHURTZ, OF KANSAS CITY, MISSOURI, ASSIGNOR, BY MESNE ASSIGNMENTS, OF ONE-HALF TO R. W. BAILEY AND C. T. JOBES, BOTH OF KANSAS CITY, MISSOURI

REFRIGERATING SYSTEM

Application filed May 18, 1923. Serial No. 639,860.

This invention relates to refrigeration, the primary object being to provide an improved refrigerating system; particularly of the continuous distillation and absorption type, the flow of the liquid and gaseous contents of the refrigerant being automatically controlled in a novel manner.

The novel construction, arrangement and combinations of parts by means of which the desired result is obtained constitute my invention. I have illustrated one form of carrying out the desired result, the details of which will be clearly apparent by reference to the following description in connection with the accompanying drawings, in which

Fig. 1 is a perspective view of a refrigeration system constructed in accordance with my invention, parts being broken away to show the interior of certain of the elements.

Fig. 2 is an enlarged, vertical, longitudinal, sectional, view through the absorber and the transfer device, parts being shown in elevation.

Fig. 3 is a sectional view through the receiver, the float-controlled fuel valve and the float being shown in section.

Fig. 4 is an elevational view of a valve seat having a port adapted to be opened to establish equalization of pressure between the still and the transfer device, a like valve being used at the bottom of the transfer device.

Fig. 5 is a similar view of a valve seat having ports for admitting rich liquor to the transfer device and permitting gas to escape from the transfer device.

Fig. 6 is a sectional view through a thermostat control for permitting weak liquor to pass from the still to the absorber.

Fig. 7 is a cross sectional view on the line 7-7 of Fig. 2, and

Fig. 8 is a longitudinal, sectional view through a thermostatically controlled expansion valve for regulating the flow of the active content of the refrigerant from the receiver to the expansion coil.

In this description the refrigerant will be referred to as aqua-ammonia, the water as the inactive or absorbent content and the ammonia as the active content of the refrigerant.

The absorber 1 initially receives relatively rich liquor, that is, water rich in ammonia. The rich liquor passes from the absorber into a transfer device 2, from which it is delivered to the still 3. Before passing to the still 3 I prefer to pass it through a preheater 4 and then through a rectifier 5 and preheater 22 so that it can take up some of the heat in the preheater and in the rectifier and enter the still at a temperature above that at which it leaves the transfer device, the purpose being to permit the rich liquor to enter the still 3 at a temperature as near as practicable to the vaporizing temperature of the ammonia so that it will require a minimum expenditure of heat at the still for vaporization.

When the rich liquor has been received in the still, it is subjected to heat from a suitable source, as, for example, from a burner 6. The source of heat for the still may be a burner of any approved construction, for rural service, I prefer an oil burner but other heaters may be employed. When the temperature of the rich liquor has been raised to the vaporization point, the vapors pass by a pipe 7 through the rectifier 5. Here the water vapors condense at a temperature higher than the condensing temperature of the ammonia or active content so the water is separated from the ammonia and gravitates back to the still. The ammonia gases pass on to a condenser coil 8 immersed in a cooling fluid (for example, water) in the tanks 9. The number of tanks utilized will depend upon the capacity of the system as obviously one tank might be employed for a given output, or any additional number of tanks might be employed for increased output or increased size of machine.

The active content is converted from the gaseous phase to the liquid phase as it passes through the condenser coil 8 and it then collects in a receiver 10 where it is fed to the expansion coil 11 through an expansion valve 13, the outlet of which is controlled by a thermostat 14. The active content passes through the coil 11 and then returns to the absorber 1, preferably through the coil 15 in the preheater tank 4 and through a cooling coil 16 in the cooling tank 17. The coil 16

enters the absorber 1 near the bottom and there is an overflow pipe 18 near the top but below the normal liquid level of the absorber 1, which merges into a coil 19 in the cooling tank 20, the coil 19 being connected to the coil 15 through the pipe 21. As the gas passes through the coil 15, it combines with the liquor and generates heat of absorption and gives up some of its heat to the liquor in the tank 4 so there is a heat exchange taking place. When the gas enters the coil 15, it mixes with the weak liquor and lowers its specific gravity below that of the weak liquor entering the loop consisting of the pipe 18, coil 19, pipe 21, coil 15, and coil 16, and, being lighter as well as being propelled by rising bubbles of gas for a distance, will flow to the absorber while the richer liquor will flow from the absorber to the loop so that the weak liquor in the absorber 1 can circulate through the cooling tanks 17 and 20 and the preheater 4. Therefore, its temperature will be reduced low enough to absorb the ammonia and thereby become an enriched liquor before it re-enters the absorber to reach the transfer device 2 preparatory to being fed back into the still.

According to the construction shown, the liquor from the rectifier 5 enters the still 3 through a heat exchanger tank 22, connected to the rectifier 5 by a pipe 23 and it flows into the still 3 through the pipe 24 at the top of the heat exchanger tank 22. The weak liquor from the still 3 is transferred to the absorber through the pipe 25, the lower end of which is submerged in the liquor in the still 3 and merges into a coil 26 in the heat exchanging tank 22, leading therefrom into the casing of a thermostatically controlled valve 27. An effluent pipe 28 from the valve 27 merges into a coil 29 in the cooling tank 17, the upper end of the coil 29 being connected to the top of the absorber tank 1 through a bushing 30, so that it delivers liquor to a pan 32 in the extreme upper part of the absorber, there being a branch pipe 31 connected to the pipe 21 and passing through the bottom of the absorber and constituting an over-flow pipe for the pan 32.

The specific details of the illustrated embodiment of my invention will now be described.

The absorber tank 1 is first supplied with a refrigerant, for example, aqua-ammonia of the requisite strength, the strength being estimated in view of the particular system in which it is to be introduced. It will be a relatively strong solution, however, for example, from 30 to 40 per cent is recommended. The aqua-ammonia can be introduced into the absorber 1 through a normally closed inlet port 34.

When the liquor thus introduced into the absorber tank 1 reaches a determined height, it fills the vertical pipe 35 in the absorber tank

whose lower end terminates slightly above the bottom thereof. From the pipe 35 the liquor overflows into the elbow 36 and through the lower end of the goose-neck 37 which communicates with one side of a port 70 38 in the valve seat 39 forming one wall of the valve chest 40. The valve chest is divided into two compartments 41 and 42 by a plate 43 having a port 79 therethrough and with its facing constituting a valve seat for a pressure-equalizing valve 44, having a port 75 therethrough and referred to hereinafter.

Slidable on the valve seat 39 is a valve 45, held in sliding contact with the seat 39 by a spring 46. The valve 45 has a port 47 which is in register with the port 38 when the transfer tank 2 is being filled through the pipe 35, elbow 36 and goose-neck 37. Therefore, as the refrigerant is initially introduced into the absorber tank 1, it will flow into the transfer device until a float 48 rises high enough in the transfer tank 2 to close communication between the absorber 1 and the tank 2. The float actuates the valve indirectly through certain mechanism which I will now describe.

A rod 49 extends practically the entire length of the tank and at its upper end it is fastened by a cross pin 50 to the valve 45 and to the valve 44. At the lower end of the rod 49 a stud or cross pin 51 connects it to a slide valve 52 movable over an inverted-T-shaped slot 53 in the wall 54 of a valve chest 55. The valve chest has its inlet opening through the slot 53 and its discharge through a pipe 56, communicating with the bottom of the pre-heater 4 although if desired, the preheater 4 can be eliminated and the pipe 56 can feed directly into the rectifier 5 instead of through the preheater tank 4 and the pipe 57 as shown. If the preheater and loop 18-19-21-15-16 are eliminated and the liquor allowed to flow directly into the rectifier or into the still, the pipe 51 will also be eliminated, in which event the liquor will overflow from pan 32 directly into the absorber. The valve 52 is located on the inside of the valve chest and it is normally urged into seating position by a spring 57. The rod loosely carries at its lower end a notched detent-receiving member 58 having two notches to receive the yielding detent 59 on the bracket 60. The detent is preferably provided at its engaging end with a roller or anti-friction device and it is urged into notch-engaging position by a spring 61, the device 58 being held against yielding by the links 62 and 63, which rock on knife edges so that the rod can only move in a vertical position and any material sidewise movement will be prevented.

The rod 49 carries collars 64 and 65. The collar 64 is adapted to receive pressure in an upward direction by a plate 66 when the float 48 rises, there being operating mechanism between the float and the plate. The operating mechanism consists of links 67 and 68 pivoted

on the side of the tank 2 and having loose connections with levers 69 and 70 pivoted on the bottom of the float. The aggregate length of the mutually connected link and lever at each side is sufficiently greater than the range of movement of the float to cause them to always be well inclined. Therefore, as the float 48 moves upward when the level in the tank 2 rises, the links 67 and 68 will swing upward, carrying with them the depending rods 71 and 72 so that the heads 73 and 74 on the lower ends of the rods 71 and 72 will engage the plate 66 causing it to lift against the collar 64 and raise collar 65 and rod 49, forcing the detent 59 out of engagement with the upper notch and allowing it to drop into the position shown in Fig. 2. This action causes final and operative movement of the rod 49 with a snap action. This upward vertical, longitudinal movement of the rod will shift all three valves 44, 45 and 52, the port 38 will be closed, the port 75 will be open with port 79, port 53 will be open and port 76 in valve seat 39 communicating with the gas escape pipe 77 in goose-neck 37, will also be closed. Therefore, communication will be established between the top of the still and the top of the transfer device through the pipe 7 and branch pipe 78, which passes through the absorber and into the chamber 41, and between the bottom of the still and the bottom of the transfer through pipe 56 and port 53. Since communication is thus established between the still and the transfer device and all other communications with the transfer device or tank 12 are cut off, it is obvious that there will be an equalization of pressure between the still and the transfer device and the rich liquor in the transfer tank 2 will flow by gravity into the still.

As the level in the transfer tank recedes, the float 48 will drop but the valve 52 will remain open until the top collars on the rods 71 and 72 strike against the plate 66, forcing the detent engaging device 58 downward and causing the detent 59 to move into the top notch with a snap action the reverse of their previous movement. This will take place only when the transfer tank 2 is about exhausted of liquor. Then the valves 52 and 44 will be closed and valve 45 open to uncover ports 38 and 76. Communication will thus be again established between the absorber and transfer device and communication between the still and the transfer device cut off.

By reference to Fig. 4 it will be observed that the port 79 complementary to the port 75 is in the form of an inverted T. This is to permit the cross pin 50 to move into the portion 80 when the transverse portions of the ports 79 and 75 are in register. In other words, it permits the pins to play up and down in the portion 80.

Attention is called to the fact that as the valve connecting rod 49 moves downward to

close the valves 44 and 52, communication will be established between the absorber and the transfer tank 2 through ports 38 and 76. At port 76, communication will be established between the transfer device and the pipe 77 in the goose-neck so that first, high pressure gas will be discharged to the absorber, and as the liquor accumulates in the transfer device, the remaining gas above the liquor may pass into the pipe 77 and into the goose-neck 37 which terminates in an inverted U-shaped loop having its bight above the pan 32 and at its extremity a tubular foraminite ring 81 submerged in the liquid in the pan 32 so that the vented gas can be absorbed by the liquid. There is a vent pipe 82 leading from the elbow 36 through the pan 32, as clearly shown in Fig. 2. In case the liquor level in the absorber falls below the lower side of the elbow 36, tendency of liquor to siphon will be checked as soon as the level in the pipe 35 is lower than the bottom of the pipe 82, for the difference in head will then result in gas bubbling from pipe 82 in the small well or pan 82' formed midway of the horizontal arm of the elbow. Likewise, any tendency of liquor to siphon from the pan 32 will be checked because the head involved at the end of the pipe 37 is greater than that at the end of the pipe 82, the submergence of which would then be the lesser, and gas will be drawn from the pipe 82 into the elbow 36. Correspondingly, preponderance of gas pressure in the absorber over that in the transfer tank when the liquor level is below the elbow 36 will be relieved through the pipe 82 in the same manner and for the same reasons.

The rich liquor entering the still becoming heated, the vapor, both ammonia and aqueous will pass into the pipe coil 7 where, as above explained, the aqueous content will be separated and the ammonia or active content will pass into the pipe 8 through the coil and into the receiver 10, then from the receiver 10 to the expansion coil 11, the flow being controlled by the thermostatically controlled expansion valve mechanism at 13-14. The thermostat 14 is shown in Fig. 8 as comprising a tube mounted on a valve casing 91 and having within a bellows 83, filled with a fluid which expands and contracts, due to heat variations. The bellows or corrugated tubing 83 has a surrounding cylinder 84, headed at both ends and normally urged in one direction in the tube by a spring 85. On the end of the bellows 83 opposite the spring there is a plug 86 slideable in the cylinder 84. On the end of cylinder 84 next the plug there is fixed a valve 87 to close the port 88 communicating through the inlet port 89 with the casing 13 and discharging through the outlet port 90, communicating with the expansion coil 11. Between the inlet and outlet port of the casing 91 there is a hand operated valve 92 which may be initially set to provide for the maxi-

5   mum flow from the receiver to the expansion coil. There is also an adjusting screw 93 in the valve casing 91, extending through cylinder 84 to contact with plug 86, to regulate the extent of movement of the member 84. Therefore, the thermostatic device shown in Fig. 8 can control the amount of the active content of the refrigerant due to variations in temperature in the zone about the expansion coil, it being understood that the expansion valve is to maintain the temperature in the refrigerator or cooling compartment constant irrespective of variations in the temperature of the outside atmosphere.

10   15   I have also provided means for regulating the heat supplied to the still. This is accomplished through an automatic valve mechanism under the control of a float in the receiver; the float, of course, being moved in response to variations of the liquid level in the receiver.

15   20   In Fig. 3 I have shown a float 94 in the receiver 10 mounted on an arm 95 carried by a rock shaft 96. On one end of the rock shaft 96 is an arm 97 in a valve casing 98. The valve casing 98 is connected to the receiver 10 by a rigid arm 99 and surrounding the rock shaft 96 is a double-cone sleeve 100 of very thin metal, having a reduced central part. 25   30   Its extremities may be welded to the receiver and to the valve casing 98 respectively and at the restricted portion of the double-cone member 100 it is welded fast to the shaft 96 as at 101. Therefore, the float can twist the shaft slightly, twisting the double-cone member 101 since the member 101 is flexible enough to permit rocking of the shaft. By welding the double-cone member to the receiver 10 and to the casing 98, it is obvious that leakage 35   40   from the receiver will be entirely eliminated.

40   45   The arm 97 controls a valve 102 in the flow line for the gas or fuel. The fuel is fed from a pipe 103 which communicates with the valve casing 98. The fuel passes from the valve casing through a pipe 104 and thence to the burner. Therefore, the mechanism shown in Fig. 3 will efficiently control the amount of fuel passed to the burners in accordance with the amount of refrigerant in 50   55   the receiver. When the refrigerant in the receiver is relatively slightly lower, the burner will be supplied with more fuel than when the level in the receiver is normal. This will be well understood by reference to Figs. 1 and 3. A hand-controlled valve 105 shown at the burner 6 may be provided for the burners if desired.

55   60   In Fig. 6 I have illustrated the interior of the thermostatically actuated valve for controlling the flow of weak liquor from the still 3 to the absorber 1. The coil 26 enters the valve casing 27 and the pipe 28 receives the discharge from the casing 27 and communicates through the coil 29 with the absorber, 65   65   as previously described, but there is a valve

70   discharge port 106 with which the pipe 28 communicates. The port 106 is adapted to be covered and uncovered by a valve 107. The valve 107 is connected to a yoke 108 which is in open link connection with a complementary yoke 109. Between the two loops of the yokes there is a thermostatic bellows element 110 and on the upper portion of the yoke 109 is a bellows thermostat 111. The bellows thermostat 111 is in communication 75   80   with the thermostatic element 112 in the still, and the bellows thermostatic element 110 is in communication with a thermostatic element 113 outside the still. The thermostat 112 is subjected to the temperature of the liquor in the still 3 while the thermostatic element 113 is subjected to the temperature of the outside atmosphere which, being lower than that of the still, will oppose the action 85   90   of the thermostatic mechanism controlled from the inside of the still. The purpose of opposing the thermostats is to provide a balance or equalization for variations in temperature so that the valve 107 will open at a lower temperature when the condensing pressure is lower as in cooler weather.

90   95   When the thermostatic elements 112 and 113 permit the opening of the valve port 106, the pressure within the still can force the weak liquor from the still through the pipe 25, through the coil 26 where there will be a heat exchange between the outgoing liquor and the incoming liquor passing from the rectifier to the still. The outgoing liquor will be forced through the pipe 28, through the coil 29, through the top of the tank 1 and into the pan 32 in the top of the tank 1 and as this liquor is very weak, it is apparent that gas which has passed into the absorber through coil 15 and pipe 16 will be reabsorbed by the weak liquor in the absorber and by the weak liquor in the pan 32 and as the level of the liquor in the pan 32 rises, it will overflow into pipe 31 and circulate with the liquor in the coil 15 thus tending to maintain the body of liquor in the absorber at a uniform normal strength and ready to be re-delivered to the transfer device as before indicated.

100   105   It is to be noted that when the charge of rich liquor passes from the transfer device, the space above the low liquid level therein contains gas which has displaced from the transfer 2 the liquid passed into the still. The opening of the port 76 permits the gas in the transfer device to escape through port 76, pipe 77, pipe 37, and perforated ring 81 so it can bubble through the weak liquor in pan 32 and be thereby absorbed. Since the gas passing from transfer device will be absorbed by the weak liquor in pan 32, there will be no appreciable increase of pressure in the absorber and expansion coil. The weak liquor from the still, coming in through pipe 29, replenishes the liquor in the pan 32, so that it 110   115   120   125   130

is always ready to absorb rapidly the gas relieved from the transfer 2.

Of course, it is to be understood that sight gauges can be provided wherever desirable, 5 but usually I would employ one for the still 3 and another for the absorber tank.

However, I do not wish to be limited to the 10 location of any particular sight gauge because, obviously, these may be placed wherever 10 desirable.

As a refinement of my invention I have provided means whereby the entire transfer device with its immediate appurtenances can be removed in a convenient manner from the absorber, and to this end I mount the entire 15 mechanism on a bottom removable plate 114 adapted to be fastened by suitable fastening devices, such as bolts 115. Suitable packing may also be employed if desired.

20 All of the parts in absorber may be drawn out with the bottom plate 114 for inspection and repairs and in order to assist in separating the parts of the valve housing, I provide the pan 32 with a funnel-shaped wall 116 (see 25 Fig. 2), whereby the pipe 78 can be tilted after it is loosened to swing the ends of the valve housing.

From the foregoing description it will be 30 apparent that the device operates in an automatic, convenient manner, that the various conditions underlying an absorption type of refrigerating plant have been taken care of by mechanism adapted to perform the requisite functions to make the device practical, and 35 that when the device is set up in accordance with my invention, it will operate without personal attention.

It will be noted that the port 106 through 40 which liquor passes from the still on its way to the absorber is quite small in proportion to the amount of liquor in the system, so that no extremely rapid depletion of the still content occurs at any time, this contributing to preserve stratification in the still, and having 45 also the effect of preventing abrupt variations of strength of the content of the still. It also tends to cause the heat of the still to be maintained at a comparatively uniform degree and 50 to prevent extreme fluctuations in the heat control. The burner is constantly in operation, and there is also a constant flow of liquor from the still to the absorber in normal operation, largely due to the small port from 55 the still.

The liquor ports of the transfer device are also comparatively small so that there is no rapid lowering of level of the absorber, and the transfer to the still is not rapid enough to produce any abrupt variation of temperature or strength of the liquor therein.

The thermostat 112 is found to work best with an expansive fluid content, rather than one operative by vaporization to operate the valve 107.

What I claim and desire to secure by Letters-Patent is:

1. In a continuous absorption refrigeration system, a still, a condenser, a liquefied gas collector, an evaporator, an absorber, and conduits connecting the above mentioned elements, in combination with still-operated means to conduct weak liquor from the still to the absorber, means responsive to variations of temperature in the still for controlling the flow of liquor from the still to the absorber, and cooperatively associated means to conduct liquor from the absorber to the still adapted to operate substantially constantly and simultaneously with the flow of liquor from still to absorber, to maintain a predetermined uniform strength of liquor in the still and in the absorber, and a heater for the still. 75

2. In a continuous absorption refrigeration system, a still, a condenser, a liquefied gas collector, an evaporator, an absorber, and conduits connecting the above named elements, in combination with still-operated means to conduct weak liquor from the still to the absorber, means responsive to variations of temperature in the still for controlling the flow of liquor from the still to the absorber to maintain an approximately uniform strength of liquor in the still and in the absorber, and cooperatively associated means to conduct liquor from the absorber to the still adapted to operate substantially constantly and simultaneously with flow of weak liquor from the still to the absorber, a heater for the still, and means associated with the collector to control the heater and responsive to variation of the quantity of liquefied gas in the collector. 95

3. In a refrigeration system, a still, a condenser, a liquefied gas collector, an evaporator, an absorber, and conduits connecting the above mentioned elements, in combination with means for maintaining a determined quantitative liquid ratio between the still, the collector and the absorber, and to maintain an approximately uniform strength of liquor in the still and the absorber, said means comprising a heater for the still, a liquid level control means operatively associated with the collector to control the heater for the still, a transfer means to conduct liquor from the absorber to the still, overflow means in the absorber to permit the absorber to discharge through the transfer means into the still upon the accumulation of a predetermined volume of liquor in the absorber, and means responsive to variations of temperature in the still for controlling the flow of liquor from the still to the absorber. 110

4. In an absorption system of refrigeration including a still, and an absorber, a transfer device for transferring liquor from the absorber into the still, the transfer device including a tank having an inlet communicating with the absorber and an outlet com- 125

- municating with the still, valve seats for the inlet and outlet, a valve outside the seat and bearing against the outlet valve seat, and a valve inwardly of and bearing against the 5 inlet valve seat, so that they will be held seated by pressures from the still and transfer device respectively, and float-actuated means within the tank connected to the valves to cause them to move in unison.
- 10 5. In means for transferring liquor from an absorber to the still in absorption refrigeration systems, a tank having liquor inlet and outlet ports, pressure balancing and venting ports, valves for the ports and float actuated means within the tank connected to the valves to cause them to move in unison, the float of the float actuated means having certain free, independent movement in either of 15 two directions before the valves are actuated, and means to oppose only initially and yieldingly movement of the valves in either direction.
- 15 6. In means for transferring liquor from an absorber to the still in refrigeration systems, a tank having an inlet communicating with the absorber, and an outlet communicating with the still, valves operative to alternately close the inlet and outlet, a valve-operating float in the tank, float operated means to cause the valves to move in unison including a motion reducing connection between the float and the valves and a device constructed to oppose initial movement of 20 the valves in each direction and to accelerate the terminal movement of the valves in each direction, said transfer device including pressure balancing means intermittently operative between the still and transfer means coordinate with the valves and valve operating means first named.
- 25 7. In a system of the character described including a still, condenser, expansion element, an absorber receiving the expanded refrigerant, and means to transfer liquor from the absorber to the still; the absorber having a loop conduit connected thereto at both ends including an ascending return portion leading into the absorber, the expanded refrigerant conduit from the expansion 30 element discharging into the lower part of said ascending portion, the transfer conduit from the absorber to the still including a portion in heat exchange relation to said ascending portion of the loop, whereby heat 35 of absorption will be conserved to aid in distillation.

In testimony whereof I affix my signature.
RALPH E. SCHURTZ.
